UNITED STATES PATENT OFFICE.

JOSEPH C. REGAN, OF NEW BRITAIN, CONNECTICUT, ASSIGNOR TO THE TRUMBULL ELECTRIC MFG. CO., OF PLAINVILLE, CONNECTICUT, A CORPORATION OF CONNECTICUT.

ELECTRIC SWITCH.

1,313,641.

Specification of Letters Patent.

Patented Aug. 19, 1919.

Application filed April 10, 1919. Serial No. 288,962.

To all whom it may concern:

Be it known that I, JOSEPH C. REGAN, a citizen of the United States of America, residing at New Britain, Connecticut, have invented a new and useful Improvement in Electric Switches, of which the following is a specification.

My invention relates particularly to inclosed switches and particularly switches having external operating handles, for instance, of the type shown in the Sutherland Patent #1,271,520.

In some of these constructions it is quite awkward and in fact difficult to pack these switches for shipment on account of the projecting handle, and in fact these handles are sometimes broken in transportation so that the switch arrives in a defective condition.

To avoid these troubles, I propose to provide a detachable handle, and it is the main object of this invention to provide a construction which may be operated in the usual way but in which the handle may be shipped detached and may be readily attached when necessary. It is a further object to make this construction at a reasonable cost and such that the parts can be assembled by any one without experience and without the possibility of error.

It is the further object to insure the rigidity and permanency of the connection.

These objects are attained by the construction comprising a hub which is mounted to rotate in the switch box and connected in any satisfactory way with the internal switch mechanism. The handle is preferably entirely outside of the box. The hub and handle are provided with interfitting bosses and shoulders and connected by a single screw.

Figure 1 is a side view of an inclosed switch embodying the improvements of my invention showing the handle in full lines in one position and in dotted lines in another position.

Fig. 2 is a fragmentary plan view showing the handle connection in section.

Fig. 3 is an end view of one form of hub.

Fig. 4 is a face view of the end of a handle formed to fit the hub of Fig. 3.

Fig. 5 shows a modified hub and handle construction, a part of the handle being shown in section.

Fig. 6 is an end view of the hub of Fig. 5. The box body 10 and the cover 11 are any

suitable type connected in any suitable manner.

The hub 12 which is connected to the interior switch mechanism is rotatably mounted in one side of the box and in the form shown provided with a flange 13.

The handle 14 is of any suitable shape and is secured to the hub by a screw 15 which passes through the aperture 16 and is seated in the threaded socket 17 in the hub.

The hub itself is preferably provided with a boss 18 which surrounds the screw socket and fits into a recess 19 in the handle.

The hub is also preferably provided with one or more lugs such as 20 and 21 which fit into recesses 22 and 23 in the handle so as to cause the handle and hub to be connected without the possibility of independent rotary movement. To afford an even bearing the face 24 of the hub may be finished and the face 25 of the handle correspondingly finished. The lugs 20 and 21 provide transverse shoulders such as 26, 27 and 28, which fit against corresponding shoulders 29, 30 and 31 on the handle so as to transmit force from the handle to the hub and the switch member contained in the box.

In the form of construction shown in Figs. 5 and 6 the hub 12' is provided with a flange 13', a screw socket 17' and a boss 18'. The handle 14' has a recess 19' for the boss and the parts are secured together by a screw 15'. In this case the hub has but a single transverse shoulder 32 which contacts with a corresponding shoulder 33 on the handle. In both forms of construction, however, it will be noted that there is a transverse shoulder located eccentrically or at one side of the center of the hub so as to provide a substantial leverage for transmitting power from the handle to the hub and the interior switch mechanism.

The handle may be provided with a slotted projection 34 adapted to be secured to the stationary slotted projection 35 on the side of the box, for instance, by means of a padlock 36. This not only prevents operation of the switch, but prevents removal of the handle.

I claim:

1. In an electric switch construction, a switch box, a hub mounted in the side thereof and provided with a central boss

and a shoulder eccentric thereof, a handle provided with a recess for said boss and a shoulder co-acting with the shoulder on said hub, and means for securing said handle to said hub.

2. In an electric switch construction, the combination of a switch box, a hub having one end exposed at one side thereof, said hub having a central screw threaded recess 10 and a shoulder at one side thereof, a handle having a corresponding co-acting shoulder and an aperture, and a screw passing through the aperture of the handle and seated in the threaded recess in the hub.

3. In a switch construction, the combination of a switch box, a hub having a central threaded recess, a boss around the entrance thereto and a transverse shoulder adjacent said boss, a handle having a corresponding shoulder and an aperture in line with said recess, and a screw passing through said aperture into said recess for holding the handle in place.

4. In an electric switch construction, the

combination of a switch box, a hub journaled in the wall of said switch box, and provided with an external flange to bear against the face of said wall, and with an external screw seat, a detachable handle engageable with the exposed face of the hub, 25 the engaging faces of said handle and hub having interlocking shoulders and a screw entered through the handle into engagement with the screw seat in the hub.

5. In an electric switch construction, a switch box, a hub journaled in the wall of said switch box and having an exposed outer end provided with a screw seat and with projecting lugs at opposite sides of said screw seat, a detachable handle engageable 35 with said exposed face of the hub and provided with shoulders to engage with the projecting lugs on the hub, and a screw adapted to be entered through the handle into engagement with the screw seat in the hub.

JOS. C. REGAN.
